UNITED STATES PATENT OFFICE.

CHARLES W. MENIGE, OF PHILADELPHIA, PENNSYLVANIA.

HYDRANT.

Application filed May 6, 1922. Serial No. 558,865.

To all whom it may concern:

Be it known that I, CHARLES W. MENIGE, a citizen of the United States, residing at Philadelphia, in the county of Philadelphia and State of Pennsylvania, have invented certain new and useful Improvements in Hydrants, of which the following is a specification.

This invention relates to hydrants and more particularly to an improvement upon the device shown in my prior Patent, No. 1,316,799, dated September 23, 1919, and includes a stop and waste cock or turn plug valve operative to control the flow of water through the hydrant and which will serve to drain the hydrant when the valve is closed so as to prevent freezing.

Among the objects of the invention are to improve the valve construction and to permit the supply pipe from the main to be connected thereto with greater facility and less cost; to encase the water conducting pipe so that soil cannot penetrate through the joints of the hydrant standard to interfere with the operation and cause excessive wear on the stop cock or turn plug of the valve and the seat thereof, and to generally improve and simplify the connection of the operating parts of the valve.

In the accompanying drawings,—

Figure 1 is a side elevation of my improved hydrant;

Figure 2 is a front elevation;

Figure 3 is a plan view;

Figure 4 is a central vertical sectional view of the hydrant with the valve in an open position, intermediate portions and the lower part of the standard being broken away;

Figure 5 is a view similar to Figure 4 but showing the valve in a closed position;

Figure 6 is a sectional view taken on the line 6—6 of Figure 4;

Figure 7 is a sectional view taken on the line 7—7 of Figure 4;

Figure 8 is a sectional view taken on the line 8—8 of Figure 4;

Figure 9 is a sectional view taken on the line 9—9 of Figure 5;

Figure 10 is a plan view of the turn plug;

Figure 11 is an elevation thereof;

Figure 12 is a sectional view taken on the line 12—12 of Figure 5, and

Figure 13 is a sectional view taken on the line 13—13 of Figure 5.

Referring to the drawings in detail, 1

represents a hollow metallic standard having formed integral therewith, an enlarged base flange 2 below which extends an enlarged bottom portion 3 designed to be embedded in the ground. The standard is provided with a nozzle or spout 4 intermediate of the upper portion 1 which tapers from the flange 2 to the upper end thereof.

The standard is provided with an internally threaded shoulder 5 preferably at the juncture of the upper portion 1 with the flange 2 so as to connect a water conducting pipe 6 thereto, said pipe extending down through the portion 3 of the standard, which portion is enlarged relative to the upper portion 1 but reduced relative to the flange portion 2 to give support to the hydrant when embedded in the ground. The lower portion 3 of the standard is shown broken away but may be extended indefinitely so as to cover the valve parts now to be described.

Connected to the lower end of the pipe 6 is a valve casing 7 having its lower end provided with a reduced externally threaded portion 8 or otherwise equipped for direct connection to a supply pipe for water from the main whereby the use of a special union or slip joint is obviated. The upper portion of the casing 7 has its bore enlarged with respect to the pipe 6 to provide an outlet chamber 9, and intermediately there is provided a circumscribing restricted portion 10 forming part of a frusto-conical valve seat 11 in which a turn plug 12 has a grinding fit.

The turn plug 12 is closed at its lower end and is formed with a chamber 13 having an inlet port 14 at one side communicating with the upper end of a conduit 15 outwardly off-set from the lower portion of the casing and communicating at its lower end with the inlet passage 16. A web 17 forms part of the seat for the turn plug through which seat the upper end of the conduit, extends and the passage 16 is normally open at the top but is closed by the lower end of the plug, thus permitting free downward movement of the plug as the surfaces of the plug and seat wear in use.

The upper end of the plug projects into the outlet chamber 9 and the upper end of the chamber 13 has outlet ports 18 opening through opposite sides of the wall of the plug into the chamber 9. The upper cylindrical portion of the plug is smaller than the chamber 9 so as to provide an annular

space around the plug at the outlets 18 in the enlarged upper bore portion of the casing 7. In this space are provided two stop shoulders or lugs 19 and 20 arranged substantially at right angles to each other and engaged by a pin 21 projecting from the turn plug so as to limit the rotation of the latter. In addition, the lower portion of the casing 7 in line with the inlet port 14 is provided with a drain port 22 in the form of an extension to which a drain tube 23 may be coupled as indicated at 24.

The upper end of the turn plug 12 is provided with a polygonal socket 25 receiving the lower end of a correspondingly shaped stem 26. The stem 26 extends through the pipe 6 and the upper portion 1 of the standard and has mounted on the upper end thereof, a frusto-conical enlargement 27 having a reduced downward projection 28 provided with a polygonal socket 29 receiving the upper end of the stem 26. Also disposed in the socket 29 between the upper end of the stem and the end wall of the socket 25 is an expansible spring 30 which normally tends to hold the plug 12 firmly seated to prevent leakage. A cap nut 31 is mounted on the upper end of the standard and has a tapered opening 32 against which the enlargement 27 seats with a grinding fit so as to prevent leakage at this point and the enlargement has a polygonal extension 33 for engagement by a detachable handle 34 by which the stem and valve may be turned to turn the hydrant on or off. An expansible spring 35 is disposed between the lower end of the projection 28 and the shoulder produced in the standard or upper end of the pipe 6 and together with the spring 30, serves to hold the enlargement 27 seated.

In the operation, the handle 34 is swung so as to turn the stem 26 through its sliding engagement with the enlargement 27 and through the connection of the lower end of the stem with the turn plug, to turn the plug so that the port 14 will be aligned with the conduit 15. Water will then flow through the passage 16, conduit 15, inlet port 14, chamber 13, outlet ports 18, chamber 9, pipe 6 around the stem 26, upper portion 1 of the standard and out through the nozzle. In this position, the pin 21 will be engaged with the stop shoulder or lug 19 as shown in Figure 7, thus limiting the turning of the valve to an open position in one direction. By turning the handle in the other direction, the valve will be closed, the pin 21 engaging the stop shoulder or lug 20 as shown in Figure 12, from the position shown in Figure 7. The plug 12 will be turned from the position shown in Figure 4 to the position shown in Figure 5, when the

upper end of the conduit 15 will be closed and the port 14 will be brought to an angular position in line with the drain 22, thus permitting the water above the valve to drain from the parts of the hydrant including the chamber 9, pipe 6 and upper portion 1 of the standard so as to prevent freezing.

A hydrant constructed in accordance with the foregoing description will be free of washers or complicated packing joints, thus eliminating the necessity for constant repairs as well as rendering the device durable and unlikely to get out of working order, and also preventing the parts from leaking.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A hydrant including a valve casing having an inlet, an outlet chamber, a frusto-conical valve seat converging downwardly from the outlet chamber and a conduit offset from and communicating with the inlet and valve seat; a turn plug in the seat provided with parts forming a passage between the conduit and outlet chamber, and means connected with the top of the plug for turning the plug.

2. A hydrant including a valve casing having an inlet, an outlet chamber, a frusto-conical valve seat converging downwardly from the outlet chamber, a conduit offset from and communicating with the inlet and valve seat, and a drain port; a turn plug in the seat provided with ports forming a passage between the conduit and outlet chamber when in open position and a passage between the outlet chamber and drain port when in closed position, and means connected with the top of the plug for turning the plug.

3. A hydrant including a valve casing having an inlet; an outlet chamber; a valve seat converging downwardly from the outlet chamber; a conduit offset from and communicating with inlet and valve seat; a turn plug in the seat provided with parts forming a passage between the conduit and the outlet chamber; means for forcing the plug to its seat; and means for turning the plug.

In testimony whereof I have signed my name to this specification.

CHARLES W. MENIGE,
